UNITED STATES PATENT OFFICE.

JOHN W. LIPPINCOTT, OF LITTLE ROCK, ARKANSAS.

VENTILATOR.

1,391,781.

Specification of Letters Patent. Patented Sept. 27, 1921.

Application filed May 20, 1919. Serial No. 298,500.

To all whom it may concern:

Be it known that I, JOHN W. LIPPINCOTT, a citizen of the United States, residing at Little Rock, in the county of Pulaski and 5 State of Arkansas, have invented new and useful Improvements in Ventilators, of which the following is a specification.

This is a continuation in part of my formally abandoned application Serial No. 10 222,689, filed March 15, 1918, for cabbage car ventilator.

My invention relates particularly to means for ventilating bulk (uncrated) cabbage when loaded (piled) in a freight car for transportation, and the objects thereof, are to provide a ventilator that will afford efficient ventilation, and, therefore, materially assist in the preservation of cabbage while in transit, and one that will also be convenient and economical to use, and I attain all 20 of these objects by the means illustrated in the accompanying drawings in which—

Figure 1 is an end view of a section of the ventilator in a normal position for use.

25 Figs. 2 and 3 are side views of several ventilator sections, each figure showing a modification of telescopically connecting the sections end to end to afford adjustability as to length.

30 Fig. 4 is a detail side view of a fragment of a ventilator section.

Similar numerals and letters refer to similar parts throughout the drawings.

The ventilator as herein contemplated 35 consists of a suitable number of sections which when placed end to end will extend from end to end throughout the longitudinal length of a maximum length freight car. The foundation of each section consists of 40 two or more triangular shaped frames, each of which is composed of a pair of legs or members 1 and 1' suitably hinged together at their upper corner or apex corner, thus forming two sides of the triangle. The

45 third side of the triangle is formed by suitably hinging a third member 2 to either of each pair of legs near its lower end and detachably connecting its other or free end with the other or companion leg, which is 50 done by providing one or more notches 3 at the free end of the third member to engage a lug or pin 4, which projects from the side of the companion leg as is shown in detail by Figs. 1 and 4. The engagement is prevented from accidental disengagement and therefore the spreading or

folding of the frame by a retaining pin 5, which passes through a hole in the third member and engages a corresponding hole in the lug 4. The object in providing several notches 3 in the third member is to afford adjustability as to the width (spread) or height of the frames. These frames may be said to be polygonal shaped frames, as the members of which they are composed 60 may be placed at any desired angle to each other. Two or more of these polygonal shaped frames are connected by covering the outside of the two members referred to as legs 1 and 1' with slats 6, suitably 65 spaced apart thus forming two reticulated sides which may be set up and locked at any desired angle to each other as is shown by end view Fig. 1 and Fig. 4.

Any suitably reticulated material may be 70 used for the sides in lieu of slats and the sides may be made more rigid and durable by the diagonal braces 7 shown in Figs. 2 and 3.

As shown in detail in Fig. 4 the legs 1 80 and 1' are blocked apart by the blocks 8 so that when the locking and engaging attachments are disengaged the third members of each section may be placed and repose in the positions indicated by the dotted lines 85 in Fig. 1, when the section may be folded for stowing, hanging on the hooks 9 near the top of the car or transportation back to point of origin.

Cars in which cabbage is usually shipped 90 vary as much as twelve feet in length, possibly more, hence, in order to adapt a given number of ventilator sections to each of the various lengthed cars it is necessary to provide considerable adjustability as to the 95 aggregate length of the ventilator sections so that the combined length of a given number of sections when placed end to end will be just long enough to extend from end to end of a maximum length car, but be 100 adapted to a shorter length car by constructing the sections so that they may telescope each other and thereby afford adjustability as to their combined length. This may be done in either of the two ways 105 illustrated by Figs. 2 and 3. It is no doubt obvious that the arrangement of the ventilator sections can be varied from that shown in either of these views, or the two methods may be combined.

In the modification illustrated by Fig. 2 110 each ventilator section is sufficiently tapered

to permit the large end of each ventilator section to telescopically receive the small end of its adjoining ventilator section and thereby afford considerable adjustability 5 (shortening) in the combined length of a number of ventilator sections—*e. g.*, the large end of the ventilator section C is adapted to telescopically receive the small end of the ventilator section B, the large 10 end of the ventilator section D is adapted to telescopically receive the small end of the ventilator section C, and this analogy applies to each additional ventilator section needed to extend from end to end of the 15 car.

In the modification illustrated by Fig. 3, however, adjustability as to the aggregate (combined) length is afforded by making alternate (every other) ventilator section sufficiently large enough so that each end thereof may telescopically receive the end of each of the adjoining smaller ventilator sections—*e. g.*, the ventilator section E is larger at both ends than ventilator sections F and 20 G, hence, will telescopically receive an end of each. The ventilator section H is larger than the ventilator section G and will, therefore, telescopically receive the end of the small ventilator section G. Likewise the 25 ventilator section I is larger than the ventilator section F and will, therefore, telescopically receive the end of the smaller ventilator section F and this analogy applies to each additional ventilator section 30 that may be needed.

As contemplated herein and shown in Figs. 2 and 3 of one of the polygonal frames is located at each end of each ventilator section and as many more at intermediate 40 points as are deemed necessary to withstand the weight and pressure of the vegetables piled thereon (and against) and each frame is provided with the third member 2 and the detachment means. As previously pointed 45 out, the functions of the third members and detachment means are to prevent the spreading and folding of the ventilator section, hence, when adjoining ventilator sections do not lap (telescope) each other this third member and the (detachable) connection (fastening) is an essential feature at each 50 end of the ventilator sections, but in cars wherein it is necessary to shorten the aggregate (combined) length of the ventilator sections by telescopically connecting the 55 ends of some or all of the ventilator sections it is obvious that if the third member 2 was in position to function at the large end (or each end of the large ventilator section) telescoping would be prohibited thereby, hence, if it is desired to telescope (lap) two adjoining sections it would be necessary to let the 60 third member, which is located at the large

end (or at both ends of the large ventilator section E) of the ventilator section continue to repose in the position indicated by the dotted lines in Fig. 1, for the effect of this telescopic connection of adjoining ventilator sections is merely to cause the large end of a ventilator section to straddle and rest upon the smaller, hence, the support of the third member is not needed at the end of the straddling ventilator section in order to prevent its tendency to spread or fold. 65

The modification illustrated by Fig. 3 has 70 an advantage over that illustrated by Fig. 2 in that the middle section E in effect merely straddles the end of each adjoining small section F and G and may, therefore, be put 75 in position after each end of the car is loaded and it may be removed as soon as the middle portion (doorway) of the car is unloaded at destination and thus greatly facilitate the work in both instances.

The ventilator herein contemplated is 80 equally well adapted to use in a refrigerated, ventilated, or a stock car, as the ventilator extends longitudinally from end to end of the car, and if used in a refrigerated car 85 wherein ice is used to preserve the cabbage, the cold air afforded by the ice will have 90 free access to and through said ventilator 95 at both of its ends, and will, therefore, freely circulate and thoroughly pervade the contents of the car, and if used in a ventilated or stock car a constant current of air will flow through said ventilator from end to end of said car when the wind is blowing or when said car is in motion, and fresh air will, therefore, thoroughly pervade the 100 contents of said car and keep them much cooler than if not provided with adequate ventilation.

Having thus described my invention what I claim and desire protected by Letters Patent of the United States is—

1. In a ventilator for piled vegetables, the combination of a plurality of sections, each section comprising inverted V-shaped end frames, one end frame of a size to telescope within the other, slats connecting said end frames to form reticulated sides, said sections being capable of arrangement in overlapping relation.

2. In a ventilator for piled vegetables, the combination of a plurality of sections, each section comprising inverted V-shaped end frames, one end frame of a size to telescope within the other, said end frames comprising legs pivoted together near their lower ends, adjustable means to space said legs apart, slats connecting said end frames to form reticulated sides, said sections being capable of arrangement in overlapping relation.

JOHN W. LIPPINCOTT.
